TOY VEHICLE

Don M. Neilson, Beaver, Utah, assignor of one-third to Abe Murdock and one-third to E. A. Griffiths, both of Beaver, Utah

Application June 28, 1937, Serial No. 150,816

10 Claims. (Cl. 280—226)

The present invention relates to an improved wheeled vehicle and has as one of its important objects to provide a simple, efficient and inexpensive toy vehicle in which the driving mechanism is operated by the weight of the rider.

A further object consists in associating with the vehicle an oscillating seat lever and an actuating member, which are fulcrumed to the body of the vehicle and are connected at one end to each other. The actuating member is also connected to a pawl and ratchet mechanism for rotating the driving axle to propel the vehicle. Additionally, yieldable means are provided for elevating the inner end of the lever and the seat upon the release of pressure therefrom in order to return the seat to its normal position.

Another object consists in associating with the driving mechanism, means to render the same inoperative so as to permit the vehicle being moved without the necessity of effecting an operative connection between the driving mechanism and the wheels of the vehicle.

Other objects and advantages of the invention will become apparent from the following description when taken in conjunction with the accompanying claims and drawings. Referring to the drawings in which is shown a preferred embodiment of the invention:

Figure 1 is a side view of a vehicle toy constructed in accordance with the invention.

Figure 2 is a sectional view taken substantially along the line 2—2 of Figure 1.

Figure 3 is a sectional view taken substantially along the line 3—3 of Figure 1.

Figure 4 is a sectional view taken substantially along the line 4—4 of Figure 1.

Figure 5 is a sectional view taken substantially along the line 5—5 of Figure 2.

Figure 6 is a sectional view taken substantially along the line 6—6 of Figure 5.

Figure 7 is a sectional view taken substantially along the line 7—7 of Figure 3.

Referring to the drawings in which like numerals indicate like parts in the several views, 45 10 designates the body of the vehicle which may be of any suitable configuration, and which for the purpose of illustration, has been shown to simulate the neck and head of a horse. The body 10 may comprise a pair of spaced wooden 50 supporting members 11 and 12 (Fig. 3) to the sides of which are secured the metallic plates 13 that may bend inwardly at their front ends to abut each other. Extending through aligned openings in the members 11 and 12 is a steering bolt or king pin 14 which has its lower

end bifurcated as at 15 to receive the axle 16 of the front wheel 17. The opposite or upper end of the bolt 14 has its head 18 extending above a wear plate 19, attached to the underside of the steering head 20 by the screws 21. The top of the body is provided with an opposed wear plate 22 secured thereto by the screws 23. The plates 19 and 22 may be slightly spaced from each other to facilitate the easy turning of the head 20 relative to the body 10. The bolt 14 is preferably provided with an enlarged polygonally shaped portion 24 which fits into a complementary formed opening in the plate 19 to secure or lock the head 20 to the bolt. Reins or flexible members 25 are shown connected to the head 20 for steering the vehicle. It will be seen that upon the rider moving the head 20 by the proper manipulation of the reins, the vehicle will turn to travel in the direction desired. Any other suitable means, such as outwardly extending handles, may be provided for actuating the head 20 to steer the vehicle.

An oscillating lever 26 is fulcrumed to the body 10 intermediate its ends as at 27, and has secured at one end thereof, a seat or saddle 28 for receiving a child or rider. The opposite end of the lever 26 is connected to a link 29 as at 30 and this link in turn is connected to a bolt 31 as at 32, which bolt is fastened to an actuating member or rod 33 by the threaded nut 34. As shown, the rod or bar 33 is pivotally connected to a bracket 35, as at 36, and this bracket may be clamped or otherwise secured to the body 10 by the retaining bolt 37 and the nut 38.

The forward end of the rod 33 may be provided with an elongated opening 39 (Fig. 2) through which the bolt 14 extends, or this end may be bifurcated to straddle the bolt in order to permit relative movement between these parts. The bolt 14 may carry the spaced washers 40 between which is confined a coiled spring 42 (Fig. 3), which normally exerts a downward pressure on the adjacent end of the rod 33 so as to raise its opposite end and at the same time elevate the seat or saddle 28 to the position shown in Fig. 1. Conversely, when the seat 28 is depressed by the weight of the rider, the spring 42 will be contracted, and when the pressure is relieved from the seat, the expansion of the spring 42 will return the parts to their normal position.

The rear end of the bar 33 is preferably provided with a series of openings 43 for receiving a bolt or pin 44 that secures a depending link 45 thereto. An arm or link 46 is arranged to be ad-

55

justably connected through the openings 41 and pin 48 with the link 45 and has its opposite or lower end journaled on the axle 49. Supporting bars or reach members 50 extend from opposite sides of the body 10 and are secured thereto by the threaded bolts 51 and nuts 52 (Fig. 2). The opposite ends of the bars 50 are preferably provided with openings through which extend the spaced sleeves 55 which surround the axle 49. The rear wheels 53 are keyed or otherwise fastened to the axle 49 so as to rotate therewith. A ratchet wheel 54 is secured to the axle 49 by the pins 54' (Fig. 4), or in any other suitable manner, and may loosely engage the bifurcated sides 56 of the arm 46. A bolt 57 extends transversely through the sides 56 and carries a pawl or dog 58 which is yieldably urged into engagement with the teeth of the ratchet wheel by a spring 59. It will be seen that when the arm 46 is moved in a counter-clockwise direction, the pawl 58 will engage the ratchet wheel to impart a rotative movement to the axle which, in turn, propels the vehicle, and that the pawl 58 is allowed to move freely over the teeth of the ratchet wheel when the arm 46 is moved in a clockwise direction.

Preferably, the ratchet wheel 54 is enclosed in a curved or oval shaped housing 60 (Fig. 5), provided with an opening 61 through which the pawl 58 extends. Slidably mounted within the housing 60, is a releasing member 62, which is movably retained in the housing by a stud 63 slidable in an opening 64. A manually actuated operating handle 65 secured to the member 62 extends through an elongated opening 66 to move the slide 62 relative to the housing. It will be seen that upon movement of the slide 62 by the actuation of the handle 65 in a counter-clockwise direction, that the slide is brought into engagement with the pawl 58 so as to move the latter away from the teeth of the ratchet wheel and thus render the driving mechanism inoperative to permit the use of the vehicle as a coaster.

Foot rests or pieces 67 extend outwardly from the sides 13 and are secured thereto by the spaced bolts or pins 68 and 69. Preferably, the bolt 69 is arranged selectively to fit into any one of a series of segmentally disposed openings 70 in the sides 13 of the body, so that the pieces 67 may be secured in any desired adjusted position relative to the seat 28. The space between the bars 50 and the rear axle 49 may be closed by the guard plates 71 which rest on the top of the sleeves 55, and are located on opposite sides of the housing 60. The sleeves 55 may be fastened at their inner ends to the concentrically disposed bosses 72 on the casing 60, by the pin 73 (Fig. 4).

The lever 26 constitutes a seat support which, upon being actuated by the up and down movement of the rider thereon, imparts a smooth mechanical driving action to the vehicle through the instrumentality of the member 33 and the pawl and ratchet mechanism. Additionally, the bolt 14 and its connection with the front wheel 17 and the head 20 constitute a steering column which may be readily actuated by the rider to control the direction of movement of the vehicle.

In using the toy vehicle, the child or rider first straddles the lever 26 so as to stand on the foot rests 67, which have been previously adjusted to permit the child to comfortably sit in the saddle 28 without his feet leaving the foot rests 67 when the child moves up and down to simulate the motion of one riding a horse so as to propel the vehicle.

It will be seen that as the weight of the rider

displaces the seat 28 from its position shown in Fig. 1, that the forward ends of the lever 26 and rod 33 are simultaneously raised and the spring 42 contracted. At the same time, the link connections 45 and 46 are lowered, and the pawl 58, by reason of its engagement with the ratchet wheel 54, causes the rotation of the rear axle 49 which imparts a forward movement to the vehicle. When the rider reaches the lowermost position, his weight will be relieved from the seat 28 and upon the removal of the downward pressure, the spring 42 will operate to return the seat 28 and its associated parts to their elevated positions.

By reason of the adjustable connection of the link 45 with both the rod 33 and the arm 46, means are provided for controlling the leverage force exerted upon the ratchet wheel 54, which may be varied depending upon the weight of the child using the vehicle. In other words, when a light weight child is operating the vehicle, the lever 45 may be connected to the arm 46 at a point near to the axle 49 so as not to require as much weight or pressure to be applied to the lever 33 to actuate the driving mechanism.

In the event that the child prefers to pull the vehicle or convert it into a coaster, it is merely necessary to move the pawl 58 out of engagement with the teeth of the ratchet wheel which is effected by actuating the handle 65 in a counter-clockwise direction. The frictional engagement of the slide 62 with the inner wall of the casing 60 tends to maintain the pawl in its disengaged position until the handle 65 is again returned to its released position.

It will be understood that the form of the invention shown and described is merely illustrative of a preferred embodiment, and that such changes may be made as fall within the purview of one skilled in the art without departing from the spirit of the invention and the scope of the appended claims.

I claim:

1. A vehicle of the class described including a body, a lever fulcrumed to the body and having a seat at one end, an actuating member fulcrumed to the body, means connecting the other end of the lever to said member, a bolt extending vertically through the body, a wheel connected to the lower end of the bolt, a steering member connected to the opposite end of the bolt for guiding the vehicle, means connecting the forward end of said member to the bolt, yieldable means for normally urging the adjacent end of the member downwardly to elevate the seat, an axle connected to the body and having wheels keyed to the ends thereof, and means operatively connecting said member to the axle to rotate the latter upon the actuation of said seat.

2. A vehicle of the class described including a body, an oscillating lever fulcrumed to the body and having a seat at one end, an actuating member fulcrumed to the body below said lever, means connecting the other end of the lever to said member, a bolt extending vertically through the body, a wheel connected to the lower end of the bolt, a steering member connected to the opposite end of the bolt for guiding the vehicle, means connecting the forward end of said member to the bolt, yieldable means for normally urging the adjacent end of the member downwardly to elevate the seat, an axle connected to the body and having wheels keyed to the ends thereof, and adjustable means operatively con-

necting said member to the axle to rotate the latter upon the actuation of said seat.

3. A vehicle of the class described including a body, an oscillating lever fulcrumed to the body and having a seat at one end, a member fulcrumed to the body below said lever, means connecting the other end of the lever to the member, a revolute bolt extending vertically through the body, a front wheel connected to the lower end of the bolt, a steering member connected to the opposite end of the bolt for guiding the vehicle, means connecting the forward end of said member to the bolt, yieldable means normally urging the adjacent end of the member downwardly so as to elevate the seat, a rear axle connected to the body and having wheels keyed to the ends thereof, means operatively connecting the member to the axle to rotate the latter, and foot rests connected to the sides of the body whereby upon the seat being depressed by the weight of the rider, the opposite end of the lever and the member are raised about their fulcrums to effect the rotation of the axle through the operating means to impart a forward motion to the vehicle, said yieldable means being contracted during this movement and being expanded when the pressure is released to return the seat to its elevated position.

4. A vehicle of class described including a body, an oscillating lever fulcrumed to the body and having a seat at one end, a rod fulcrumed to the body below said lever, means connecting the other end of the lever to the rod, a revolute bolt extending vertically through the body, a wheel connected to the lower end of the bolt, a steering member connected to the opposite end of the bolt for guiding the vehicle, means connecting the forward end of said rod to the bolt, yieldable means for normally urging the adjacent end of the rod downwardly to elevate the seat, an axle connected to the body and having wheels keyed to the ends thereof, means operatively connecting the rod to the axle to rotate the latter upon the actuation of said seat, and means to render the operating means inoperative.

5. A vehicle of the class described including a body, a lever fulcrumed to the body and having a seat at one end, a rod fulcrumed to the body below said lever, means connecting the other end of the lever to the rod, a revolute bolt extending vertically through the body, a wheel connected to the lower end of the bolt, a steering member connected to the opposite end of the bolt for guiding the vehicle, means connecting the forward end of said rod to the bolt, yieldable means for normally urging the adjacent end of the rod downwardly to elevate the seat, an axle connected to the body and having wheels keyed to the ends thereof, a ratchet wheel fastened to the axle, said rod having a depending link connected to the rear end thereof, an arm journaled on the axle and connected to said link, a pawl carried by said arm and arranged to engage said ratchet wheel, and foot rests connected to the sides of the body whereby upon the seat being depressed by the weight of the rider the opposite end of the lever and the rod are raised and the arm carrying the pawl is forced downwardly to rotate the axle and impart a forward motion to the vehicle, said yieldable means being contracted during this movement and operable when the pressure is released to expand and return the seat to its elevated position.

6. A vehicle of the class described including a body, an oscillating lever fulcrumed to the body

and having a seat at one end, a rod fulcrumed to the body below said lever, means connecting the other end of the lever to the rod, a revolute bolt extending vertically through the body, a wheel connected to the lower end of the bolt, a steering member connected to the opposite end of the bolt for guiding the vehicle, means connecting the forward end of said rod to the bolt, yieldable means for normally urging the adjacent end of the rod downwardly to elevate the seat, an axle connected to the body and having wheels keyed to the ends thereof, a ratchet wheel fastened to the axle, said rod having a depending link adjustably connected to the rear end thereof, an arm journaled on the axle and adjustably connected to said link, a pawl carried by said arm and arranged to engage said ratchet wheel, and foot rests connected to the sides of the body whereby upon the seat being depressed by the weight of the rider the opposite end of the lever and the rod are raised and the arm carrying the pawl is forced downwardly to rotate the axle and impart a forward motion to the vehicle, said yieldable means being contracted during this movement and operable when the pressure is released to expand and return the seat to its elevated position.

7. A vehicle of the class described including a body, an oscillating lever fulcrumed to the body and having a seat at one end, a rod fulcrumed to the body below said lever, means connecting the other end of the lever to the rod, a revolute bolt extending vertically through the body, a front wheel connected to the lower end of the bolt, a steering member connected to the opposite end of the bolt, a steering member connected to the opposite end of the bolt for guiding the vehicle, means connecting the forward end of said bar to the bolt, yieldable means for normally urging the adjacent end of the rod downwardly to elevate the seat, a rear axle connected to the body and having wheels keyed to the ends thereof, a ratchet wheel fastened to the axle, said rod having a depending link connected to the rear end thereof, an arm journaled on the axle and connected to said link, a pawl carried by said arm and arranged to engage said ratchet wheel, foot rests connected to the sides of the body whereby upon the seat being depressed by the weight of the rider the opposite end of the lever and the rod are raised and the arm carrying the pawl is forced downwardly to rotate the axle and impart a forward motion to the vehicle, said yieldable means being contracted during this movement and operable when the downward pressure is released to expand and return the seat to its elevated position, and a releaser associated with the pawl for maintaining the same out of engagement with the ratchet wheel.

8. A vehicle of the class described including a body, a steering wheel connected to the body, a lever fulcrumed intermediate its ends to the body and having a seat mounted thereon, an actuating member fulcrumed intermediate its ends to the body, said lever and actuating member extending lengthwise of the body, means interconnecting the forward end portions of the actuating member and said lever, yieldable means between the body and the forward end of the actuating member for normally maintaining the seat in its raised position, an axle connected to the body and having wheels fastened thereto, and driving means operatively connecting the actuating member to the axle so as to rotate the latter upon the depression of the seat, said yieldable

means acting to return the seat to its raised position upon the downward pressure being released from said seat.

9. A vehicle of the class described including a body, a steering wheel connected to the body, a lever fulcrumed intermediate its ends to the body and having a seat mounted thereon, an actuating member fulcrumed intermediate its ends to the body, said lever and actuating member extending lengthwise of the body, means interconnecting the forward end portions of the actuating member and said lever, yieldable means between the body and the forward end of the actuating member for normally maintaining the seat in its raised position, an axle connected to the body and having wheels fastened thereto, driving means operatively connecting the actuating member to the axle so as to rotate the latter upon the depression of the seat, said yieldable means acting to return the seat to its raised position upon the downward pressure being released from said seat, and means mounted on the axle

and slidably connected to the driving means for rendering the latter inoperative.

10. A vehicle of the class described including a body, a steering wheel connected to the body, a lever fulcrumed intermediate its ends to the body and having a seat mounted thereon, an actuating member fulcrumed intermediate its ends to the body, said lever and actuating member extending lengthwise of the body, means interconnecting the forward end portions of the actuating member and said lever, yieldable means between the body and the forward end of the actuating member for normally maintaining the seat in its raised position, an axle connected to the body and having wheels fastened thereto, driving means operatively connecting the actuating member to the axle so as to rotate the latter upon the depression of the seat, said yieldable means acting to return the seat to its raised position upon the downward pressure being released from said seat, and means adjustably connecting the driving means to the actuating member.

DON M. NEILSON.
